FOUNTAIN PEN

Solomon M. Sager, Glencoe, Ill.

Application January 18, 1936, Serial No. 59,673

11 Claims. (Cl. 120—46)

This invention relates to an improved type of fountain pen provided with an improved filler unit adapted to be engaged on one end of the fountain pen barrel in cooperating relation with the inner 5 end of the shank of the fountain pen feed bar.

It is an object of this invention to provide a fountain pen wherein an enclosed filler mechanism is removably engaged as a unit on one end of the fountain pen barrel.

10 It is also an object of this invention to provide a fountain pen including a barrel having removably engaged on one end thereof a closure cap or casing containing a filling means which is operable by a collapsible plunger the operating end 15 of which is normally disposed to seat within a recess provided in said casing or cap.

It is furthermore an object of this invention to provide a fountain pen with a filler unit in the form of a fountain pen barrel closure cap containing a bulbous rubber-like structure having packing ends and including a flexible strap spring having an operating plunger connected therewith and slidably projectable outwardly through an opening in the cap to permit operation of the 25 bulbous structure for filling the fountain pen barrel and collapsible into a release position permitting the bulbous structure to normally remain in an expanded or inflated position to obviate setting of the rubber-like bulb material which often occurs in fountain pens wherein the bulb structure remains compressed during the time 30 the operating lever is seated in a closed position.

It is an important object of this invention to provide a fountain pen wherein the barrel has removably engaged on one end thereof a casing or cap for enclosing a compressible bulbous rubber-like structure closed at one end by a packing head and having the other end or base formed to act as a packing to prevent leakage of ink from the 35 barrel into the casing and grooved for holding an apertured closure disc or plate to expand the base into a tight fit with the casing and also serve as an air control when the bulbous structure is operated by means of a collapsible and manually 40 slideable plunger connected with a strap spring seated on the exterior of the normally inflated bulbous structure to serve as a protection for the bulbous structure as well as a means for assisting in the return of the plunger into an outwardly projecting operating position after a compression of the bulbous structure to cause 45 ink to be drawn into the fountain pen barrel.

Other and further important objects of this 50 invention will be apparent from the disclosures in the specification and the accompanying drawings.

The invention (in a preferred form) is illustrated in the drawing and hereinafter more fully 55 described.

On the drawing:

Figure 1 is a longitudinal sectional view of a fountain pen embodying the principles of this invention and showing parts of the fountain pen in elevation.

Figure 2 is a fragmentary elevational view of one end of the fountain pen barrel having an improved filler unit removably secured thereto.

Figure 3 is a longitudinal sectional view of the filler unit and showing the bulbous structure partially collapsed by means of the operating plunger.

Figure 4 is an elevation of the bulbous filler structure removed from its protecting casing and having the operating plunger removed.

Figure 5 is an enlarged fragmentary detail section taken on line V—V of Figure 2 illustrating the operating position of the pivoted plunger in dotted lines.

Figure 6 is a fragmentary detail section taken 20 on line VI—VI of Figure 5.

Figure 7 is a fragmentary sectional view similar to that illustrated in Figure 5 covering a modified form of plunger or operating means for actuating the bulbous structure of the filler unit.

As shown on the drawing:

The improved fountain pen comprises an elongated hollow barrel 1 which is internally threaded at one end and which has integrally formed on the opposite end an externally threaded rim or neck 2. Threaded into the internally threaded end of the barrel 1 is the threaded shank 3 of a section 4. Secured in overlapping relation in the section 4 is a pen point 5 and a feed bar 6. The feed bar 6 is provided with an elongated shank 7 which projects through the section 4 and extends longitudinally through the major portion of the ink chamber of the barrel 1 to within a short distance of the outer end of the barrel. For the purpose of protecting the pen point 5 when the fountain pen is not in use, a closure cap 8 is removably engaged over the pen point end of the fountain pen barrel.

Removably engaged on the threaded neck end 2 of the fountain pen barrel 1 is a filler unit comprising a chambered housing or casing 9 which is closed at its outer end and internally threaded at the inner open end thereof. Provided in the wall of the casing 9 is an opening 10 and a recess 11 communicating therewith. Seated within the casing 9 is an elongated or oval shaped bulbous rubber-like structure 12 closed at one end by an integral top or packing head 13 of solid material and formed to tightly fit within the closed end of the casing 9 and serve as a packing when necessary. Integrally formed on the opposite end of the bulb structure 12 is an internally grooved packing base 14 the bottom of which is provided with an opening 15. Seated within the inter-

nally grooved base 14 is a washer or plate 16 which expands the elastic base into a tight sealing fit with the inner wall of the casing 9 to prevent leakage of ink into said casing around the bulb and out through any casing openings. The washer 16 is provided with a small central aperture 17 which is in register with the opening 15 and provides an outlet or an inlet for the air chamber within the rubber-like bulb 12.

10 Seated against the exterior of one side of the bulb 12 is a flexible resilient metal strap spring 18, the ends of which project into or are imbedded in the solid bulb head 13 and the neck portion of the base 14 as clearly illustrated in Figure 1. Integrally formed on opposite sides of the middle portion of the strap spring 18 is a pair of ears or lugs 19 and 20 between which the head end of an operating lever or plunger 21 is pivotally engaged. Formed on one of the side plates 22 forming the head of the plunger 21 is a detent 23 (Figure 6) which is adapted to lockingly seat in an opening 24 provided in the ear or lug 19 to hold the lever or plunger 21 latched in the operating or projecting position illustrated in Figure 3. Also provided in the lug 19 is an aperture 25 which is adapted to lockingly receive the detent 23 for the purpose of holding the lever or operating plunger 21 latched in the closed position illustrated in Figure 1.

15 30 Normally the operating lever or plunger 21 is in the closed position illustrated in Figure 1 permitting the bulb 12 to normally assume an inflated position. When it is desired to fill the fountain pen, the cap 8 is removed and the pen point is projected into a supply of ink. The operating plunger 21 is then pivotally swung outwardly into the dotted line projecting position, illustrated in Figure 5, without causing deflation or compression of the bulb 12. When in its outwardly projecting position, the plunger 21 is adapted to be slidably projected inwardly through the opening 10 to cause the flexible strap spring 18 to compress or collapse the resilient rubber-like bulb 12 as illustrated in Figure 3. 35 40 45 Upon release of the operator's finger from the depressed plunger 21 the bulb 12 together with the deflected strap spring 18 acts to project the plunger 21 outwardly to permit the same to be again manually pushed inwardly to repeat the collapsing operation of the bulb. These operations are repeated until the ink chamber of the fountain pen barrel 1 is filled. After the filling of the fountain pen, the plunger 21 is swung into the position illustrated in Figure 1 without causing compression of the spring 18 or the bulb 12 and seats in the recess 11, in which position the plunger is held latched by means of the locking detent 23 seating in the aperture 25 of the member 19.

50 55 60 65 70 75 Figure 7 illustrates a modified form of the operating means for actuating the bulb 12 and the strap spring 18 associated therewith. The modified form of actuating means comprises two operating levers or plungers 26 each of which is provided with a detent 27. The operating plungers 26 are pivotally supported on lugs or ears formed on the side margins of the spring 18. Normally the operating plungers 26 are swung downwardly in opposite directions to seat in a recess provided in the casing 9 without disturbing the inflated position of the bulb. When it is desired to actuate the filling means, the plungers 26 are swung outwardly into the dotted line positions of Figure 7, without compressing the spring 18 or the bulb 12, in which position they

are engaged back to back to provide a plunger having a larger bearing contact with the spring 18 for operating the flexible filling bulb 12.

It will be understood, of course, that the various details of construction may be varied 5 through a wide range without departing from the principles of this invention, and it is therefore not the purpose to limit the patent granted hereon otherwise than necessitated by the scope of the appended claims.

10 I claim as my invention:

1. A fountain pen comprising an elongated barrel, a section in one end of the barrel, a pen point and a feed bar secured in the section, said feed bar having an integral elongated reduced 15 shank extending through the barrel to within a short distance of the outer end thereof, a filler unit removably engaged on the end of the barrel opposite the section, said filler unit comprising a casing closed at the outer end and open at the 20 inner end, with said inner end removably engaged on the end of the fountain pen barrel, said casing having an opening and a recess formed in the wall thereof, a resilient rubber-like bulbous structure enclosed by the casing and having an 25 apertured end thereof positioned adjacent the end of the feed bar shank within the barrel, a resilient strap spring in the casing seated against the side of the bulbous structure, and an operating member 30 movably connected with the strap spring and projecting through the casing opening to permit operation of the bulbous structure for filling the fountain pen barrel, said operating member when not in use being adapted to be moved into an out-of-the-way position to seat 35 in the recess provided in said casing.

2. A fountain pen comprising an elongated barrel, a section in one end thereof, a pen point and a feed bar secured in the section, said feed bar having an elongated reduced shank extending 40 through the barrel to within a short distance of the end thereof, a filler unit engaged on the end of the barrel opposite the section, said filler unit comprising a casing closed at one end and open at the opposite end for engagement on the 45 barrel, said casing having an opening and a recess formed in the wall thereof, a bulbous structure in the casing having a head integrally formed on one end thereof seated in the closed end of the casing, an apertured disk seated in 50 the opposite open end of the bulbous structure adjacent the end of the feed bar shank, a resilient strap spring seated against the side of the bulbous structure and having the ends thereof embedded in the material forming the bulbous 55 structure, and operating means pivotally connected with the strap spring and projecting through the casing opening to permit compression of the bulbous structure to cause filling of the fountain pen, said operating means when not 60 in use adapted to be moved into a position to seat in the recess provided in said casing.

3. A fountain pen comprising a barrel including a section in one end thereof, a pen point engaged in the section, a feed bar in contact 65 with the pen point and engaged in the section, said feed bar having an integral portion thereof extending through the section and through substantially the entire length of the ink chamber of the fountain pen barrel, a casing closed at 70 one end and open at the opposite end removably engaged on the end of the fountain pen barrel opposite the section, a bulbous filling structure seated in the casing for coaction with the feed bar, a strap spring seated on the exterior of the 75

bulbous structure and having the ends thereof embedded in the material forming the bulbous structure, and operating means connected with the strap spring and operable through the casing 5 for actuating the bulbous structure to cause filling of the fountain pen.

4. In a fountain pen, a filler unit comprising a casing closed at one end and open at the opposite end for engagement on one end of the 10 fountain pen barrel, a bulbous structure engaged in the casing and having a solid head integrally formed on one end thereof to seat in the closed end of the casing, said bulbous structure having an internally grooved base integrally formed 15 on the opposite end thereof, an apertured disk seated in the grooved base, a spring seated against the exterior of the bulbous structure and having the ends thereof embedded in the bulbous structure head and base, and operating means 20 pivotally connected to the spring and slidably projecting through an opening in the casing to permit operation of the bulbous structure to cause filling of the fountain pen barrel, said casing being provided with a recess for receiving 25 the operating means when the same is not in use.

5. In a fountain pen, a filler unit comprising a casing closed at one end and open at the opposite end for engagement on one end of the 30 fountain pen barrel, a bulbous structure engaged in the casing and having a solid head integrally formed on one end thereof to seat in the closed end of the casing, said bulbous structure having an internally grooved base integrally formed on the opposite end thereof, an apertured disk seated in the grooved base, a spring seated against the exterior of the bulbous structure and having the ends thereof embedded 35 in the bulbous structure head and base, operating means pivotally connected to the spring to permit operation of the bulbous structure to cause filling of the fountain pen barrel, said casing being provided with a recess for receiving the operating means when the same is not in 40 use, and latch means between the operating means and said spring for holding the operating means in latched position in both an operating position and when in a collapsed position when seated in the recess provided in the casing.

50 6. In a fountain pen, a filler unit comprising a casing closed at one end and open at the opposite end, with said open end of the casing removably engaged on one end of the fountain pen barrel, a bulbous structure engaged in the casing 55 closed at one end and open at the opposite end, an apertured disk seated in the open end of the bulbous structure and expanding the same into sealing contact with the interior of the casing, a spring contacting the bulbous structure and partly embedded therein, and operating 60 means connected with the spring and projecting through an opening provided in the casing to permit operation of the bulbous structure from the exterior of the casing to cause filling 65 of the fountain pen.

7. In a fountain pen, a filler unit for removable engagement on one end of the fountain pen barrel, said filler unit comprising a casing, a bulbous structure in the casing closed at one end 70 and having an internally grooved base formed on the opposite end, an apertured disk in the

internally grooved base, a flexible member seated against the exterior of the bulbous structure and partially embedded therein, an operating member pivotally connected with the flexible member and accessible through an opening in the casing to permit operation of the bulbous structure, and latching means between the flexible member and the operating member to hold the operating member latched either in an operating position or in a collapsed position. 10

8. A filler unit for use in a fountain pen, said filler unit comprising a casing closed at one end and open at the opposite end, said casing having a communicating opening and recess formed in the wall thereof, a bulbous structure engaged in the casing and having a solid head formed on one end thereof for seating in the closed end of the casing and also having an internally grooved base formed on the opposite end thereof, an apertured disk seated in said base, a spring member seated 20 against the side of the bulbous structure and having portions thereof embedded in said bulbous structure, an operating plunger pivotally connected to said spring member and slidably projecting through the opening in the casing to permit operation of the bulbous structure, and latching means between the spring member and said operating plunger for holding the operating plunger latched either in operating position or in a collapsed position when seated in the recess 30 provided in the casing.

9. In a fountain pen, a filler unit for engagement on one end of the fountain pen barrel, said filler unit comprising a casing, a bulbous structure in the casing, packing means integrally 35 formed at both ends of the bulbous structure and of greater diameter than the bulbous structure for providing tight seals with the casing, a flexible member seated against the bulbous structure between the packing means, and a manually reciprocable operating member connected with the flexible member for operating the bulbous structure to cause filling of the fountain pen, said operating member adapted to be seated in the casing wall or moved into an operating position projecting outwardly from the casing without causing deflation of the bulbous structure when in either 40 of said positions. 45

10. A fountain pen filler unit comprising a casing, a bulb in the casing, a packing head formed 50 on one end of the bulb and sealingly contacting the interior of the casing, a grooved packing base formed on the opposite end of the bulb, an apertured disc engaged in the grooved base to expand the same into sealing contact with the interior of the casing, a strap spring in the casing seated against the bulb, and an operating member pivoted to the spring. 55

11. A fountain pen filler unit comprising a casing, a bulb in the casing, a packing head 60 formed on one end of the bulb and sealingly contacting the interior of the casing, a grooved packing base formed on the opposite end of the bulb, an apertured disc engaged in the grooved base to expand the same into sealing contact with the interior of the casing, a strap spring in the casing seated against the bulb, an operating member pivoted to the spring, and means for locking the operating member in retracted and in extended positions. 65
